Palmer, Washington, D. C.

Application December 27, 1939, Serial No. 311,208

12 Claims. (Cl. 102—29)

The present invention relates to a grenade of the type having a pull ring pin for normally holding the cocked hammer thereof inoperative and the control arm thereof locked against removal from the fuse head of the grenade. In actual use the control arm is first freed of the pull ring pin by detaching the latter from the fuse head however without removal of hand pressure from the control arm which at this time still holds the hammer in its desired cocked relation. Thereafter and pursuant to command the grenade is thrown, thus removing the hand pressure from the control arm. In flight the cocked hammer retracts. In retracting towards its firing position the cocked hammer first operates to disconnect the control arm from the fuse head and subsequently fires the primer. Where there is a prolonged time interval between the removal of the pull ring pin and the command to throw the grenade, hand pressure on the part of the operator against the control arm is the only expedient within control of the operator and should such hand pressure be removed even for a split second, the hammer is inadvertently freed and automatically retracts ultimately bringing about an undesired firing operation obviously dangerous and detrimental to the operator. In instances where a command is given for removal of the pull ring pin and thereafter no further command is rendered to throw the grenade, the operator is also placed in a dangerous circumstance with an active grenade in hand. Instances of this kind often occur and since the operator is under great strain at this time involuntary and inadvertent removal of hand pressure from the control arm has on many occasions terminated tragically to the operator. Thus the invention has for its principal and important object to provide easily accessible and conveniently operable lock means for the control arm to prevent the latter from being accidentally operated by the cocked hammer even though hand pressure therefrom is removed. The invention has another object the provision of a relatively durable and rugged safety lock for controlling the operation of the control arm when the latter is freed of the pull ring pin. More specifically the invention has as another important object the provision of a hand grenade having at its upper end a rotary annular member comprising latching means in the form of a manipulatable crank having its latching arm normally held in a non-latching position at one side of and free of the control arm of the grenade and held against rotation by a conveniently accessible pull ring pin disconnectably or removably threaded through the cap of the control arm, the fuse head or guard and the projecting means integral with the annular member and extending laterally of and above the latter adja-

cent to the cap of the control arm and the fuse head, the latching means pursuant to the removal of the pull ring pin from the cap fuse head and projecting means, adapted to be actuated by thumb pressure of the hand grasping the grenade for rotatably and removably shifting the latching arm thereof over the control arm to hold the latter latched on the fuse head independent of any manual pressure on the control arm. The invention further comprehends as an object the provision of a rotary lock advantageously actuated when desired by finger pressure of the throwing hand of the operator. Further functional and structural features, advantages, and objects of the invention relate to the provision of stop means to prevent involuntary latching of the control arm when the pull ring is still carried by the fuse head, the provision of braking means to hold the control arm locking means selectively in predetermined positions against inadvertent rotary displacement, and the provision of a beaded hammer adapted to be conveniently and safely raised and satisfactorily brought to its cocked relation under the control arm during assembly. Other functional, structural and salient features, advantages, and objects of the invention will appear from the teachings of the following detailed description considered in the light of the accompanying drawings wherein:

Fig. 1 is a perspective view of the grenade according to the invention, showing the safety lock unlocked from the control arm.

Fig. 2 is a sectional view on the line 2—2 of Fig. 1, however illustrating the pull ring pin means mounted on the fuse head and holding the beaded hammer cocked independent of the control arm.

Fig. 3 is a fragmentary view of Fig. 2 illustrating the retraction of the cocked hammer towards its firing position after the pull ring pin means has been withdrawn for the automatic removal of the control arm when the grenade has been thrown or is in flight.

Fig. 4 is a front fragmentary elevational view of the grenade.

Fig. 5 is a side elevational view of Fig. 4 however showing parts thereof in section.

Fig. 6 is a plan view of Fig. 4 showing parts in section and broken away to illustrate the braking or supplementary locking means, and illustrating the safety lock unlatched from the control arm.

Fig. 7 is a view of the grenade, showing the pull ring pin means removed and the safety lock latched over the control arm.

Fig. 8 is a sectional view showing the manner of raising the beaded cocked hammer.

Fig. 9 is a plan view of the cocked hammer receiving the pull hook, and

Fig. 10 illustrates the manner in which the hammer is moved from its firing position to its cocked position under the control arm.

Illustrative of the embodiment disclosed, the hand grenade per se is of the conventional type and usually comprises the scored and sealed casing or fragmentatious body 10 containing the usual explosive charge 11 communicating with a burning time fuse 12 suitable for a hand grenade. 5 This fuse is fitted within a fixed tube 13 carried by the threaded bushing 14 of the fuse head generally designated 15 which is threadably and tightly secured in part within and against the contracted frusto-conical upper end 16 of the 10 casing.

The conical or tapered end or neck 16 is provided with a relatively smooth conical outer bearing face or seat 17 for rotatably guiding the finned and fragmentatious annular but frusto-conical or 15 tapered annular collar or sleeve 18 of the control arm safety locking means generally denoted 19 which includes the offset latching arm 20 adapted to be reciprocably rotated over the control arm broadly denoted 21 having cap 22 provided with 20 the curved lip 23 removably anchored by the lip 24 of the fuse head 15 and including the downwardly and outwardly projecting reinforced or ribbed backing 25 extending within close proximity to but spaced from the outer interrupted but 25 relatively smooth casing 10.

More specifically however the control arm safety locking means 19 in fact may be said to characterize the tapered ring or sleeve 18 provided with the radially and outwardly projecting 30 interrupted ribs or fins 26 which have a double function, to wit, one, they may be conveniently gripped by the operator and, two, they render the sleeve more shatterable.

It should be noted that the latch arm 20 of 40 the safety locking means is integral with boss or lug 27 (Fig. 6) extending from the rotary sleeve 18. The arm 20 is angularly offset in respect to boss 27 and is spaced from the outer surface of the sleeve, thus defining the gap or 45 pocket 28. This arm 20 also has a roughened or corrugated surface 29 to facilitate gripping thereof. The latch for removably hooking or latching over the backing 25 of the control arm is preferably cast integral with the tapered or 50 frusto conical sleeve or ring 18 and is in the form of an elbow or conveniently manipulatable crank arm as shown embodying the outwardly and substantially radially extending lug or boss 27 and the latching arm 20 which appreciably and 55 laterally overhangs lug 27 and in angular relation therewith and consequently the latching arm is continuously in a spaced relation from the fragmentatious sleeve 18.

The firing hammer 30 is pivoted on the fixed 60 fulcrum pin 31 carried by the fuse head. This hammer is normally urged to its firing position against the head of the explosive exciting primer or cartridge 32 by the helicoidal spring 33 having one end 34 abutting hammer 30 and another end 65 34' abutting the fuse head. However such normal automatic firing action is prevented by the pull ring pin means and more particularly by the shanks of the cotter pin 35 thereof which is removably mounted or threaded in the spaced perforated ears 36 of cap 22 and the perforated and spaced ears 37 of the fuse head straddled by ears 36. Hence with the cotter pin 35 holding the control arm 21 in fixed position on the fuse 70 head 15, the cotter pin acts as a stop (Fig. 2).

and resists the retraction of the hammer towards its firing position.

Where however the cotter pin is removed from the fuse head upon application of an outward thrust to the swingable pull ring 38 carried thereby, the backing 25 of the control arm 21 constitutes means to prevent retraction of the hammer provided proper hand pressure is applied against the backing and in a direction towards the barrel shaped body of the grenade. 10

With the pull ring pin means withdrawn from the cap and the fuse head and upon discarding of the grenade, hammer 30 due to the action of spring 33 first automatically disengages cap 22 from the fuse head 15 and continues to retract to 15 ultimately fire primer 32.

In instances where the pull ring pin means is withdrawn and where it is desired to hold the hammer in its non-firing relation, namely, cocked, without however applying hand pressure to the 20 backing of the control arm, this may be accomplished by rotating the safety locking means 19 from the position shown in Figs. 1 and 6 to the position shown in Fig. 7, that is, the latching lug or arm 20 may be actuated by the thumb of the 25 hand grasping the grenade to rotate sleeve 18 counterclockwise whereby gap 28 receives backing 25 and lug 20 is to the rear of backing 25 and constitutes stop means for the latter, thus 30 maintaining the control arm 21 on the fuse head to hold the hammer against retraction even though hand pressure be removed from the offset backing 25. Thus the control arm is held positively and safely locked independent of any 35 manual pressure.

Where the command is given to prepare the grenade for flight, the operator at this time, actuates the latching arm 20 to rotate sleeve 18 clockwise. This is accomplished by the thumb of the hand grasping grenade and the grenade 40 is now ready to be thrown in that the control arm is now unlocked or unlatched at which time of course hand pressure is applied to the control arm until the grenade is actually discarded for flight upon command, and during the course of 45 actuating or manipulating the latching crank by the thumb of one hand of the operator such operation can be facilitated by applying to one of the ribs 26 a proper finger thrust of the same 50 hand of operator grasping the body of the grenade either for latching the control arm or backing or for unlatching the latter preparatory to flight.

For effectively holding the rotatable sleeve 18 in predetermined latching and non-latching positions of the control arm, supplementary locking means is provided, which supplementary locking means comprises a spheroid or ball 39 (Fig. 6) adapted to enter either of the locking notches 40 and 41 in the fixed frusto-conical seat 16. This spheroid is slidably arranged within the socket 42 of lug 27 containing the normally expanded spring 43 which continuously urges spheroid 39 towards the truncated neck 16. Thus in the non-locking position of the crank comprising the 55 latching arm 20 and the lug 27 integral therewith, spheroid 39 is urged to interlock with the wall of notch 41. Hence the rotary safety locking means 19 is prevented from accidental rotary 60 displacement in the non-latching relation of lug 65 or arm 20.

Where the latching arm is deliberately shifted to latch the control arm 21, spheroid 39 is snapped out of notch 41 and yieldingly rides along the 65 conical surface 17 until it reaches socket or notch 70

40 at which time it is urged to interlock with the wall of this socket and it follows that the safety locking means 19 is positively prevented from accidental displacement in the latching relation 5 of lug 20 thereof with the control arm 21. Hence it may be stated that the rotatable locking means 19 is reciprocable and is positively braked or latched automatically and substantially at the end of each stroke since the spring actuated 10 spheroid disengageably and automatically interlocks with either of the notches 40 or 41 when the sleeve 18 is oscillated. Such oscillation however is limited by reason of a stop pin 44 carried at the upper contracted end of the grenade. This 15 stop pin 44 acts on the end walls 45 or 46 of the elongated guide slot 47 in the rotary sleeve 18 and of course projects into this slot. In other words, rotatable reciprocation of the sleeve is limited by pin 44 which cooperates with the end 20 walls 45 and 46 severally and only at the end of each stroke, and thus spheroid 39 common to the locking notches 40 and 41 is automatically locked to upper contracted end 16 of the grenade. According to the invention, the firing hammer 25 30 is provided with hollow head or socket 50 adapted to removably receive the hooked end 51 of the tool 52. Hence it is an easy matter to raise hammer 30 to its cocked position and underneath the backing 25 of the control arm 21. 30 It follows that even though the grenade contains the explosive charge the hammer may be safely lifted and safely positioned under the control arm subsequently to be retained by the cotter pin.

The showing in Fig. 1 of the hand on the 35 grenade illustrates one way in which the grenade may be held. In actual practise, preparatory to discarding the grenade for flight at a time when the control arm is unlatched, the control arm may be in the palm of the hand holding the 40 grenade which of course can be of any suitable material known in the art for example cast iron or the like and if desired the latching crank comprising arm 20 and lug 27 may be of a suitable steel although the invention is not limited 45 to any particular material. If the latching crank is of a suitable steel, it may be welded onto the sleeve 18 which may be of cast iron or steel or of any known material in the grenade art.

In the inoperative relation of the firing hammer 30, the latching arm 20 is normally at one side and free of the backing 25 (Fig. 6) and rotation of the truncated sleeve 18 of the safety lock 19 is also prevented by the split shank of the cotter pin 35 removably threaded through 50 the alined perforations or apertures 36' in the spaced ears 36 of the cap 22 of the control arm 21, the alined openings or apertures 37' in the spaced ears 37 of the fuse head, and through the 55 perforation or aperture 38' in the bracket or lug 18' integral with and extending above the body of the fragmentatious sleeve 18, the arrangement being such that in the assembled relation of the control arm 21 and the rotary locking sleeve, the cotter pin receiving openings 37' of the spaced 60 ears 37 of the fuse head or guard 15 are alined with the openings 36' in the cap and in alinement or registration with the opening 38' in the upstanding bracket or projecting means 18' integral with the rotary sleeve 18.

70 While the invention has been described in detail and reference has been made to a specific application thereof, it is to be understood that the invention herein disclosed is not limited to such specific application and it is intended that 75 all matter contained in the above description or

shown in the accompanying drawings shall be interpreted as illustrative and not in a limiting sense.

We claim:

1. In a hand grenade, the combination of, a 5 casing having a neck, a head secured to said neck, a spring controlled firing hammer pivoted to said head, a control arm having a cap removably seated on said head and including a depending backing disposed contiguous to said casing and 10 cooperating with said hammer to hold the latter in a non-firing position, a locking member rotatably sustained on said neck and comprising projecting means extending laterally of and integral with said member and disposed adjacent 15 said cap and head, said cap, head, and projecting means having alined apertures, said locking member having a crank arm comprising an outwardly extending lug and including a finger manipulatable latching arm integral with said lug and laterally overhanging the latter in angular relation thereto, and a pin removably threaded through said apertures to prevent reciprocable rotation of said member and movement of said 20 latching arm over or from said backing. 25

2. In a hand grenade, the combination of, a 30 casing having a neck, a head secured to said neck, a spring controlled firing hammer pivoted to said head, a control arm having a cap removably seated on said head and including a depending backing disposed contiguous to said casing and cooperating with said hammer to hold the latter in a non-firing position, an annular locking member rotatably sustained on said neck and comprising projecting means extending laterally of and integral with said member and disposed adjacent 35 said cap and head, said cap, head, and projecting means having alined apertures, said locking member having a crank arm comprising an outwardly and substantially radially extending lug and including a finger manipulatable latching arm integral with said lug and laterally overhanging the latter in angular relation thereto, and a pin removably threaded through said apertures to normally prevent reciprocable rotation 40 of said member and movement of said latching arm over or from said backing, said latching arm pursuant to removal of said pin from said cap, head and projecting means adapted to be reciprocated over and from said backing for latching or 45 unlatching said control arm respectively. 50

3. In a hand grenade, the combination of, a 55 casing having a neck, a head secured to said neck, a spring controlled firing hammer pivoted to said head, a control arm having a cap removably seated on said head and including a depending backing disposed contiguous to said casing and cooperating with said hammer to hold the latter in a non-firing position, an annular locking member rotatably sustained on said neck and comprising projecting means extending laterally of and integral with said member and disposed adjacent 60 said cap and head, said locking member having a crank arm comprising an outwardly extending lug and including a finger manipulatable latching arm integral with said lug and laterally overhanging the latter in angular relation thereto, said cap, head, and projecting means having alined apertures, said locking member having a plurality of widely spaced and substantially radially extending ribs, and a pin removably threaded through said apertures to normally prevent reciprocable rotation of said member and movement of said latching arm over or 65 70 75

- from said backing, said ribs and said latching arm adapted to be manipulated pursuant to removal of said pin from said cap, head and projecting means to rotate said member to shift said latching arm to its latching position over said backing or to its unlatched position away from said backing.
4. In a hand grenade, the combination of, a casing having a neck, a head secured to said neck, a spring controlled firing hammer pivoted to said head, a control arm having a cap removably seated on said head and including a depending backing disposed contiguous to said casing and coooperating with said hammer to hold the latter in a non-firing position, a truncated annular locking member rotatably sustained on said neck and comprising projecting means extending laterally of and integral with said member and disposed adjacent said cap and head, said cap, head, and projecting means having alined apertures, said locking member having a crank arm comprising an outwardly extending lug and including a finger manipulatable latching arm integral with said lug and laterally and appreciably overhanging the latter in angular relation thereto, a pin removably threaded through said apertures to prevent reciprocable rotation of said member and movement of said latching arm over or from said backing, said member pursuant to the removal of said pin from said cap, head and projecting means adapted to be rotated upon finger manipulation of said latching arm to shift the latter to its latching position over said backing or to its unlatching position away from said backing, and means to limit rotational displacement of said member relative to said backing pursuant to removal of said pin from said cap, head, and projecting means.
5. In a hand grenade, the combination of, a casing having a frusto-conical neck, a head secured to said neck, a spring controlled firing hammer pivoted to said head, a control arm having a cap removably seated on said head and including a depending backing disposed contiguous to said casing and cooperating with said hammer to hold the latter in a non-firing position, a locking frusto-conical member rotatably sustained on said neck and comprising projecting means and extending above and integral with said ring and disposed adjacent said cap and head, said cap, head, and projecting means having alined apertures, said locking member having a crank arm comprising an outwardly extending lug and including a finger manipulatable latching arm integral with said lug and laterally overhanging the latter in angular relation thereto, and a pin removably threaded through said apertures to prevent reciprocable rotation of said member and movement of said latching arm over or from said backing.
6. In a hand grenade, the combination of, a casing having a neck, a head secured to said neck, a spring controlled firing hammer pivoted to said head, a control arm having a cap removably seated on said head and including a depending backing disposed contiguous to said casing and cooperating with said hammer to hold the latter in a non-firing position, a reciprocable locking member movably sustained on said neck and comprising projecting means extending laterally of and integral with said member and disposed adjacent said cap and head, said cap, head, and projecting means having alined apertures, said locking member having a crank arm comprising an outwardly extending
- lug and including a finger manipulatable latching arm integral with said lug and laterally and appreciably overhanging the latter in angular relation thereto, a pin removably threaded through said apertures to prevent reciprocable displacement of said member over or from said backing, said member pursuant to the removal of said pin from said cap, head and projecting means adapted to be shifted upon finger manipulation of said latching arm to move the latter to its latching position over said backing or to its unlatching position away from said backing, and means to limit reciprocable displacement of said member relative to said backing pursuant to removal of said pin from said head, cap, and projecting means.
7. In a hand grenade, the combination of, a casing having a neck, a head secured to said neck, a spring controlled firing hammer pivoted to said head, a control arm having a cap removably seated on said head and including a depending backing disposed contiguous to said casing and cooperating with said hammer to hold the latter in a non-firing position, an annular locking member rotatably sustained on said neck and comprising projecting means extending laterally of and integral with said member and disposed adjacent said cap and head, said cap, head, and projecting means having alined apertures, said locking member having a crank arm integral therewith and comprising an outwardly extending lug and including a finger manipulatable latching arm integral with said lug and laterally and appreciably overhanging the latter in angular relation thereto, a pin removably threaded through said apertures to prevent reciprocable rotation of said member and movement of said latching arm over or from said backing, said latching arm pursuant to the removal of said pin from said cap, head and projecting means adapted to be rotated upon finger manipulation to its latching position over said backing or to its unlatching position away from said backing, means to limit rotational displacement of said member relative to said backing pursuant to removal of said pin from said head, cap and projecting means, and spring controlled means operable substantially at the limits of said rotational displacement for automatically locking said member against accidental displacement thereof relative to said casing.
8. In a hand grenade, the combination of, a casing having a neck having spaced sockets, a head secured to said neck, a spring controlled firing hammer pivoted to said head, a control arm having a cap removably seated on said head and including a depending backing disposed contiguous to said casing and cooperating with said hammer to hold the latter in a non-firing position, an annular locking member rotatably sustained on said neck and comprising projecting means extending laterally of and integral with said member and disposed adjacent said cap and head, said cap, head, and projecting means having alined apertures, said locking member having a crank arm bodily movable therewith and comprising an outwardly extending lug and including a finger manipulatable latching arm integral with said lug and laterally and appreciably overhanging the latter in angular relation thereto, a pin removably threaded through said apertures to prevent reciprocable rotation of said member and movement of said latching arm over or from said backing, said member pursuant to the re-

5 removal of said pin from said cap, head and projecting means adapted to be rotated upon finger manipulation of said latching arm to shift the latter to its latching position over said backing or to its unlatching position away from said backing, means to limit rotational displacement of said member relative to said backing pursuant to the removal of said pin from said head, cap and projecting means, and spring controlled 10 spheroid means carried by and movably arranged in said lug for severally interlocking with said sockets to prevent accidental displacement of said member relative to said casing.

10 9. In a hand grenade, the combination of, a 15 casing having a truncated neck at the upper end of said casing, a head secured to said neck, a spring controlled firing hammer pivoted to said head, a control arm having a cap removably seated on said head and including a depending 20 backing disposed contiguous to said casing and cooperating with said hammer to hold the latter in a non-firing position, a truncated annular locking member rotatably sustained on said neck and comprising projecting means extending above and laterally of and integral with said member and disposed adjacent said cap and head, said cap, 25 head, and projecting means having aligned apertures, said locking member having a crank arm integral therewith and comprising an outwardly 30 extending lug and including a finger manipulatable latching arm integral with said lug and laterally and appreciably overhanging the latter in angular relation thereto, a pull ring pin removably threaded through said apertures to prevent reciprocable rotation of said member and movement of said latching arm over or from said 35 backing, said member pursuant to the removal of said pin from said cap, head and projecting means adapted to be rotated upon finger manipulation of said latching arm to shift the latter to its latching position over said backing or to its unlatching position away from said backing, said member comprising an elongated slot, and pin means carried by said neck and projecting into said slot to limit rotational displacement of said 40 member relative to said backing pursuant to removal of said pin from said cap, head and projecting means.

40 10. In a hand grenade, the combination of, a 45 casing having a neck, a head secured to said neck, a spring controlled firing hammer pivoted to said head, a control arm having a cap removably seated on said head and including a depending 50 backing disposed contiguous to said casing and cooperating with said hammer to hold the latter in a non-firing position, a locking annular member rotatably sustained on said neck and comprising projecting means extending laterally of and integral with said member and disposed adjacent 55 said cap and head, said cap, head, and projecting means having aligned apertures, a pin threaded through said apertures to hold said member locked against displacement relative to said control arm, said member having a latching arm normally disposed in non-latching relation relative to said backing and at one side thereof in said locked relation of said member relative to said control arm, said member pursuant to the removal of said pin from said cap, head and projecting means adapted to be rotated in one direction upon finger manipulation of said latching arm to move the latter to its latching position over said backing and thereafter adapted to be shifted in an opposite direction to move said latching arm to its unlatching position away from and clear of said backing, and means to limit rotatable displacement of said member relative to said backing pursuant to removal of said pin from said head, cap and projecting means.

5 11. In a hand grenade, the combination of, a 10 casing having a neck, a head secured to said neck, a spring controlled firing hammer pivoted to said head, a control arm having a cap removably seated on said head and including a depending 15 backing disposed contiguous to said casing and cooperating with said hammer to hold the latter in a non-firing position, a locking member movably sustained on said neck and comprising projecting means extending laterally of and integral 20 with said member and disposed adjacent said cap and head, said cap, head, and projecting means having aligned apertures, a pin removably threaded through said apertures to hold said member locked against displacement relative to said control arm, said member having a latching arm normally disposed in non-latching relation relative to said backing and at one side thereof in said locked relation of said member relative to said control arm, said member pursuant to the 25 removal of said pin from said cap, head and projecting means adapted to be shifted upon finger manipulation of said latching arm to move the latter to its latching position over said backing and thereafter to its unlatching position away from and clear of said backing, and means to limit displacement of said member relative to said backing pursuant to removal of said pin from said head, cap and projecting means.

10 12. In a hand grenade, the combination of, a 15 casing having a neck, a head secured to said neck, a spring controlled firing hammer pivoted to said head, a control arm having a cap removably seated on said head and including a depending 20 backing disposed contiguous to said casing and cooperating with said hammer to hold the latter in a non-firing position, a locking annular member rotatably sustained on said neck and comprising projecting means extending laterally of and integral with said member and disposed adjacent 25 said cap and head, said cap, head, and projecting means having aligned apertures, a pin threaded through said apertures to hold said member locked against displacement relative to said control arm, said member having a latching arm normally disposed in non-latching relation relative to said backing and at one side thereof in said locked relation of said member relative to said control arm, said member pursuant to the removal of said pin from said cap, head and projecting means adapted to be rotated in one direction upon finger manipulation of said latching arm to move the latter to its latching position over said backing and thereafter adapted to be shifted in an opposite direction to move said latching arm to its unlatching position away from and clear of said backing, and means to limit rotatable displacement of said member relative to said backing pursuant to removal of said pin from said head, cap and projecting means.
